SNOWMOBILE

Anthony D. Mackeen, Drummondville South, Quebec,
Canada, assignor to Skiroule Limitee, Wickham, Quebec, Canada

Filed Feb. 9, 1971, Ser. No. 114,099

Term of patent 3½ years

Int. Cl. D12—03

U.S. Cl. D14—24

FIG.1

FIG.5

FIG. 1 is a top plan view of the snowmobile;
 FIG. 2 is an elevational view of one side of the snowmobile;

FIG. 3 is a bottom plan view;

FIG. 4 is a front end elevational view; and
 FIG. 5 is a rear end elevational view.

The side opposite to that shown in FIG. 2 is a mirror image thereof.

I claim:

The ornamental design for a snowmobile, as shown and described.
